HINGE

La Verne E. Clayton, Rockford, Ill., assignor to Amerock Corporation, Rockford, Ill., a corporation of Illinois

Filed May 4, 1964, Ser. No. 79,804

Term of patent 14 years

(Cl. D10—9)

FIGURE 1 is a front elevational view of a hinge embodying my new design.

FIG. 2 is a top view of the hinge.

FIG. 3 is a side view of the hinge as viewed from the left in FIG. 1.

FIG. 4 is an enlarged perspective view of the hinge.

The dominant feature of the design resides in the solid line portion.

I claim:

The ornamental design for a hinge, substantially as shown and described.
